PREBUILT MATTRESS AND BOX SPRING BORDER MACHINE

Gustav A. Boettcher, Jamaica, N. Y.

Substituted for abandoned application Serial No. 48,318, November 5, 1935. This application September 30, 1936, Serial No. 103,453

2 Claims. (Cl. 112—117)

This invention refers to prebuilt mattress and box-spring borders and an automatic machine for making the same, and particularly to that type of machine wherein a frame carrying fabric

5 material supply rolls, positively operated feed rolls and wind up rolls for receiving the stitched material past a group of sewing instrumentalities upon the machine so as to stitch predetermined designs upon said material and simultaneously 10 stitch together several layers of material to form the prebuilt border.

The main object of my invention is to provide a machine of the character indicated which is small and compact in form and capable of economically 15 producing prebuilt mattress borders by simultaneously producing two such borders, if desired.

Another object is to have such a machine which is capable of producing either a pair of mattress 20 or box-spring borders, or one of each simultaneously, or simply a single mattress or box-spring border alone.

A further object is to provide such a machine with facilities for producing substantially equal 25 stitches along various directional lines and curves in different types of designs which are stitched into the borders.

It is also an important object to produce a mattress or box-spring border which is built up of 30 such heavy and substantial fabric layers which are also so tightly stitched, and particularly stitched according to such novel and effective designs that such a border is both heavy enough to prevent detection of springs located within the 35 mattress involved and so resilient as to automatically straighten or flatten out when released from a compressed or folded condition.

In addition, it is also an object of the invention to provide a machine of the indicated type which 40 is exceedingly simple and accessible in construction, when considering the class of work it is designed to do, and is so efficient withal, as to turn out prebuilt borders at high speed.

Among other objects, it is also intended that 45 the invention shall include automatic electrical means for stopping operation of the machine upon breakage of any thread on the same.

Furthermore, the invention contemplates providing the machine with automatic means for 50 tightening the thread as each stitch is sewed in order to draw each stitch very tight.

It should be pointed out that the present machine also includes manually controlled electrical means governing the operation of individual 55 needles or groups of needles in the machine so

that it is possible to allow certain needles or groups thereof to remain idle while other needles are actively used for stitching a single border or portions of a design thereon.

Other objects and the many advantages inherent in the construction, arrangement of parts and operation as well as in the borders involved in the invention will appear more fully in detail as this specification proceeds.

In the accompanying drawings forming part 10 hereof,

Fig. 1 is a front elevation of a machine embodying the invention and its salient features in a practical form.

Fig. 2 is a side elevation of the same machine 15 as seen from the left.

Fig. 3 is an enlarged fragmentary section of the machine as taken on line 3—3 of Fig. 1.

Fig. 4 is an enlarged detail of certain gearing and adjustment means therefor only partly 20 shown at the intermediate left portion of Fig. 2.

Fig. 5 is a top plan view of the machine as seen from above in Fig. 1.

Fig. 6 is a diagrammatic front elevation of the machine as shown in Fig. 1, with much of the 25 detail and many obscuring parts omitted to clarify the view which is intended to reveal the unity and movement of a special movable frame or fabric carriage carrying the fabric supply, feed and wind up rolls.

Fig. 7 is an enlarged fragmentary side view of the portion of the machine shown in Fig. 2 intermediate the upper and lower portions thereof, omitting several obscuring parts in order to disclose the manner in which the intermediate portion 30 of the mentioned movable frame is mounted, the operating and control cams and members for the fabric feed rolls also being included.

Fig. 8 is an elevational plan view of the same parts illustrated in Fig. 7.

Fig. 9 shows the same mechanism as seen from the left in Fig. 8.

Fig. 10 is a fragmentary view of the upper right portion of the frame of the machine shown in Fig. 1, illustrating an electrical contact device for 45 closing an electric circuit upon breakage of a thread while the machine is running.

Fig. 11 is a side view, partly in section of the same parts as in Fig. 10.

Fig. 12 is an enlarged perspective view of an 50 electric contact lever of Figs. 10 and 11.

Fig. 13 is a plan view of an automatically operated switch of the machine and a switch box which is shown without its cover.

Fig. 14 is a sectional view of the same switch 55

and box with the cover of the switch box in place.

Fig. 15 is a sectional view of a rotary timing contact and its protecting box, which form parts of the machine.

5 Fig. 16 is a transverse section of the same on line 16-16 in Fig. 15.

Fig. 17 is an electrical diagram of the machine embodying the invention.

10 Figs. 18 and 19 illustrate typical designs of stitched mattress and box-spring borders as made according to the invention by the mentioned machine.

Fig. 20 is a section of the border of Fig. 18, for example, as taken on line 20-20.

15 Fig. 21 is a fragmentary view of the eccentric and its rod which are obscured in Fig. 1 at the right although partly shown at the right in Fig. 5 in section.

20 Throughout the views, the same reference numerals indicate the same or like parts. The present application is a substitute for my application Serial No. 48,318, filed November 5, 1935.

25 In the practice of my invention, a pair of stationary frames 1, 2 are secured together below by a connecting frame or bridge 3 and at their upper portions by one or more tie rods or runners similar to 4, which in turn form the supporting means within the outline of the machine for such known sewing instrumentalities such as 30 shuttle races, shuttle holders and shuttles generally indicated at 5. Inasmuch as these latter parts do not directly involve the novelty herein they will simply be referred to hereafter as the lower sewing instrumentalities.

35 Upon the frames 1 and 2 are secured rigid upper extensions 6 and 7 which are surmounted by a wind up reel support assembly, generally indicated at 8 and including a plurality of reel supports similar to 9.

40 A main drive shaft 10 passes through the main frames 1 and 2, carrying a pulley 11 (Fig. 5) upon one end driven from a pulley 12 (Figs. 1 and 2) mounted upon an arm 13 (Fig. 1) fast upon frame 2 and is in turn rotated by a belt 45 14 upon a larger pulley 15 rigid with said pulley 12. The belt 14 is driven by a clutch pulley 16 of a clutch 17 in line with an electric motor or other source of mechanical power 18, supported upon the lower portion of the machine at 19.

45 50 The main drive shaft 10 is provided with a pair of eccentrics 20, 20 provided with yokes 21, 21 (Fig. 1) which project rearwardly in the form of a pair of arms 22, 22 (Fig. 5) inter-connected by a bar 23 to which certain of the lower sewing instrumentalities such as the shuttle holder bars 24, 24 are attached with the result that upon rotation of the main shaft and said eccentrics said shuttle holder bars will be reciprocated between the shuttle races 25, 25 of the lower sewing instrumentalities.

55 An apron 26 is mounted upon the frames in order to protect fabric from becoming caught and torn by contact with any of the lower mechanism of the machine. Adjacent to the apron upon the frames 1 and 2 is secured a horizontal plate 27, upon which the sewing or stitching of fabric is performed.

60 Upon the pulley 11 (Fig. 5) of the main drive shaft 10 is connected a crank rod 28 (Figs. 2 and 5) in the form of an upwardly extending rod which is eccentrically pivoted by a crank pin 28' to said pulley upon one side thereof.

65 At the upper end of said crank rod 28, as shown in Fig. 2, said rod is pivoted to a lever 29

fixed upon an operating shaft 30 which is supported in upper frame members 6 and 7.

This operating shaft is intended to reciprocate and thereby actuate upper sewing instrumentalities as will be immediately explained. Between upper frame members 6 and 7 are also provided a pair of rigid bars or tie rods 31 fixed in said frame members and having a plurality of guide frames similar to 32 and 33 rigidly secured upon said bars, as may be noted in Fig. 3. In the frames 32 are provided slideably mounted vertical presser foot guide rods 34 connected upon their lower ends by means of a presser foot 35 which is adapted to reciprocate vertically with said guide rods. In order to facilitate the operation of the presser-foot and also cushion the operation of the guide rods, springs similar to 36 are provided, engaging between the upper guide rod bearings 37 and collars 38 fast upon said guide rods 34, with the result that said springs will tend to resiliently resist raising of the presser foot. Upon shaft 30 a plurality of cams similar to 39 are fixed adjacent to frames 32 and adapted to engage beneath rollers similar to 40 upon blocks 41 secured upon the upper ends of said guide rods. Obviously, upon partial or reciprocal rotation of operating shaft 30, cams 39 engaging rollers 40 will tend to raise the guide rods and then allow the same to drop alternately so that the presser foot 35 is reciprocated above plate 27.

40 Upon the same shaft 30 a plurality of levers similar to 42 are secured and are connected to operating rods 43 which in turn are connected at lower ends to a horizontal needle bar 44 carrying groups of needles as at 45, 45. In order to guide said needle bar in its movements a plurality of needle bar guide rods 46, 46 are slidably supported in the frames 33 with the result that upon partial repeated rotation of operating shaft 40 30 the needle bar with its needles is reciprocated vertically in perfectly accurate manner, the presser foot and stitching plate 27 being, of course, provided with corresponding apertures for said needles. In order to feed threads to the needles, 45 spools similar to 47 are placed in position upon supports 9 (Fig. 3) with the thread 48 passing downwardly therefrom past tension devices similar to 49 rigidly secured upon a transverse bar 50 fast upon frame members 6 and 7 and thence 55 passing behind an auxiliary take-up bar 51 secured upon needle bar guide rods 46 by means of members 52. The thread is passed downwardly from said bar 51 behind a main take-up bar 53 and through insulating porcelain guides 54 from which the thread is again brought upward and passed through other porcelain guides 55 in the main take-up bar 53. Said latter take-up bar is also secured to the needle bar guide rods 46 by means of attachment members 56 60 and thence again downwardly to the needles 45.

65 The purpose of thus passing the thread behind the auxiliary take-up bar and similarly past the main take-up bar and upwardly through the same and finally down to the needles is to tighten the stitches as they are sewed in the fabric 57 beneath the presser foot 35, it being immediately evident that when the needle bar 44 is reciprocated vertically by operation of shaft 30 guide rods 46 and therefor also the auxiliary take-up bar as well as the main take-up bar will likewise be reciprocated with the needle bar. When the needle bar descends with its needles to sew a stitch, the take-up bars will also be lowered so as to produce a slack in the thread, and when 70 75

the needle bar again is raised for the next stitch, the take-up bars will naturally rise therewith so as to take up the slack in the thread and, in fact, draw the same very tight, with the result that each stitch is quite tight before the next is produced. The porcelain guides 54 and 55 could, of course, be substituted by any other desired guide means through which the thread might pass, but it should be pointed out that while the 10 upper inlets 55 in the take-up bar as well as the auxiliary take-up bar itself rise when the needles are raised, the guides similar to 54 are not raised therewith, and it is for this reason that the slack is taken out of the thread when the needles and 15 take-up bars are raised after producing a stitch.

As may be seen in Fig. 3, the attachment members 52 and 56 have manually adjustable screws 52' and 56', respectively, for adjusting the location of these members along the guide 20 rods 46 in order to adjust the heights of the main and auxiliary take up bars to the proper slack and take up of the threads, depending on the kind and thickness of the goods to be operated upon as well as the kind and size of the 25 thread used for each particular run of work.

It may occasionally occur that a thread will break at the moment it is tightened and it is quite evident that the machine should immediately be stopped if this occurs, for otherwise defective sewing will take place with one or two 30 rows of stitches entirely missing from the fabric. In order to promptly stop the machine and also render such cessation of its operation entirely 35 automatic, electrical means are incorporated, as will hereinafter be explained.

Returning now to the main shaft 10, it may be well to consider the feeding of fabric through the machine, which occurs by using a pair of feed rollers similar to 58 and 59 and resiliently 40 held in contact with fabric 57 by means of manually adjustable means including a spring 60. These feed rolls are supported in a movable frame consisting of pair of main side members 61 and 62 which have, in front of the machine 45 a downwardly projecting frame generally indicated at 63 secured thereto for supporting fabric reels similar to 64, 65 upon shafts 66', 67', and similar reels may be mounted on shafts 66 and 67 when desired. The frame 63 is provided with 50 a plurality of hook bearings similar to the centrally located bearings 62' and 69' for supporting the shafts of the reels. The lower shaft 66 is provided with a pulley 60' by which it may be rotated or retarded in rotation, and the collar 61' serves to keep the shaft from running 55 out of the bearings, the shaft terminating in bearing 62' where it meets the ends of shaft 66. The reel 64 is pinned to this shaft and may be rotated by the pulley 63', while a collar 64' retains the shaft in place. Similarly, the shaft 60 67 is retained in place by a collar 70' and may be rotated by the pulley 71', while terminating within bearing 69', in which it meets the end of shaft 61. The reel 65 is pinned to this shaft 65 and rotatable by pulley 68' and a collar 65' serves to retain the shaft in place in its bearings.

Upon the rear of the movable frame members 61, 62, adjacent, to the location of the fabric 70 feed rolls are fixedly mounted a pair of upwardly extending support members 68, 69 surmounted by bearings 70, 71 carrying a shaft 72. Upon this shaft is fixed a pulley 73 adjacent to one end and a fabric wind up reel 14 secured at 74' 75 so that said shaft may be driven by rotating pul-

ley 73 for the purpose of driving the fabric wind-up reel in order to receive stitched fabric from the feed rolls after having been drawn past the sewing instrumentalities. Shaft 72 also carries a second fabric wind-up reel 75 freely rotatably mounted upon the same between locating collars 72' and 73' and provided with a pulley 76 similar to pulley 73. These pulleys are preferably connected to the main shaft by means of belts similar to 77 at the location generally indicated at 78 in Fig. 5 so as to provide for positive rotation of the fabric wind-up reels from the main shaft. In Fig. 2 the belt 77 is shown as brought past a take-up device 79 for adjusting the slack of said belt, said device being pivoted at 80 in the side bar 69.

Hence, if upper and lower fabrics 80, 81 of a mattress border generally indicated at 82 in Figs. 18, 20 are individually rolled up on supply reels 65, 64 respectively (Fig. 1) and a filler 20 layer 83 simultaneously supplied between said fabrics from a roll on the floor in front of the machine or from a supply reel not shown, said fabric assembly will be drawn past the sewing instrumentalities upon the machine by the feed 25 rolls upon the movable frame, similarly to the fabric 51 in Fig. 3. This movable frame supports the feed rolls together with the supply reels just mentioned, as well as the fabric wind-up reels and is in effect a balanced movable 30 frame. The means for supporting the frame are provided in the form of extensions upon the ends of the tie rods or runners exteriorly to frame members 1, 2, said extensions 84, 85 passing through the movable frame members 61, 62 35 which are thus slidably mounted thereon. Upon frame member 1 an exteriorly disposed stud 86 is secured and together with one of the extensions 85 supports a gear box 87, as may be seen in Fig. 6. Adjacent to the gear box 87 is secured a hand wheel upon the drive shaft 10 in order to make it possible to manually raise or lower the needles and otherwise slowly operate the machine for adjusting the same preparatory to sewing upon said machine in regular opera- 45 tion.

The gear box is provided upon one side thereof with a cam 89 adapted to rotate between a pair of rollers 90, 91 mounted upon a bar 92 connected to the movable frame already described. Upon the same shaft of said cam is secured a gear 93 for positively rotating the cam and this gear meshes with a second gear 94 which in turn meshes with the further gear 95. Upon the shaft of gear 95 is mounted a worm- 55 gear meshing with a worm fast upon the main drive shaft 10 (which gear and worm are not shown in order to avoid obscuring the figures) with the result that the rotation of the drive shaft will cause rotation of the cam and consequent sliding reciprocating movement of the balanced movable frame upon extensions 84, 85 of runners 4. If the feed rolls simultaneously feed the fabric past the sewing instrumentalities while the cam just described is rotated by the drive 60 shaft and interposed gearing, the sewing will not occur in a straight line but will be modified according to the movements of the movable frame derived from the shape and speed of rotation of said cam 89.

When the machine is operated it will perhaps be seen that the speed of rotation of the feed rolls will have its due effect upon the length of the stitches and particularly when the stitches do not occur in a straight forward direction. 75

Examples of various designs for the sewing to be produced by the machine are shown in Figs. 18-20, the design in Fig. 18 being a mere zigzag pattern using four needles simultaneously, two of the needles being secured upon the forward edge of the needle bar while the other two are secured to the rear thereof so that the first of the needles sew in advance of the other two and thus produce the different portions of the pattern. In connection with this design there is no necessity for adjusting the machine in order to equalize the stitches throughout, but in the design shown in Fig. 19, for example, certain expedients are incorporated so that the sewing will occur along the straightforward portions 96 at approximately the same rate as along the diagonal portions 97 upon the border 98. In either case the sewing, of course, advances along the mattress border in the direction indicated by the arrows.

In order to provide a normal feeding movement to the feed rollers for straightforward stitching a fabric feed cam 99 is fixed upon main drive shaft 10 and is engaged by a roller 100 upon a rockably mounted bracket 101 pivoted to frame member 61 of the balanced movable frame at 102. A link 103 is connected to a slotted portion 104 in said rockable bracket 101 at one end and at the other end of the link is connected to a rocking member 105 pivoted upon said frame 61 and provided with a pawl 106 adapted to engage one-way teeth of a ratchet 107. Upon the same shaft with ratchet 107 is a gear 108 rigid with said ratchet and mounted therewith upon a sleeve (not shown) so as to be together rotatable upon the shaft 109 which is continuous with feed roller 58. Gear 108 meshes with a relatively larger gear 111 which in turn is rigid with a further gear 112 so as to rotate therewith upon a stub shaft 113, the gear 112 in turn meshing with another relatively larger gear 114 rigid with shaft 109 with feed roller 58. In order to transmit the rotation imparted to said feed roller to the other feed roller, these rollers are provided with meshing gears 115, 116.

Upon rotation of the main shaft the cam 99 will cause bracket 101 to rock with consequent reciprocation of pawl 106 so as to feed the sprocket 107 in a forward direction at the rate of one tooth, for example, at each movement. The feed rollers are thus positively driven through said ratchet while a pawl 117 mounted above said ratchet engages the same so as to prevent any return movement of said ratchet. The rate of feeding thus ensuing is quite proper for the zigzag or diagonal lines of stitches 118 in the design of Fig. 18 or in a diagonal lines 97 in the design of Fig. 19 because sidewise movements of the balanced movable frame carrying the fabric reels and feed rollers due to rotation of design cam 89 will suffice to produce proper lengths of stitches in said diagonal lines.

However, the feeding of the fabric at the rate of a single tooth for each movement of the cam 99 and pawl 106 would be too slow when the straightforward stitching at 96 in Fig. 19 should be performed because the stitches would be entirely too close and short. The same condition 70 would be true in curved designs where the lines or rows of stitches would gradually turn from oblique or nearly transverse directions into straightforward sewing and in order to speed up the feeding movement of the feed rollers, a control cam 119 is introduced to cause an increased

movement of the pawl 106 with consequent engagement of two or three teeth thereof instead of merely one tooth at each reciprocation of said pawl.

The rocking member 105 has a rearward extension 128 provided with an adjusting screw or the like at 129 adapted to engage upon the control cam 119. The latter cam has a gear 110 rigid therewith meshing with the gear 111 of the gear assembly previously described for driving the feed rolls, and is rotatable on a stud 130 on frame member 61. Upon said cam 119 is cut a gap 131, so that during rotation, this gap will come beneath the adjustment screw 129, allowing the screw to descend into said gap. The screw normally is raised out of contact with the peripheral surface of control cam 119 during each feeding stroke of pawl 106, but is brought down upon said cam periphery during each return movement of said pawl after having fed 20 sprocket 107 forward one tooth, and it is obvious that the extent of return movement allowed the pawl will determine the amount of subsequent forward movement of the sprocket which will be caused by the pawl, inasmuch as the strokes of 25 said pawl will thus be controlled. Its forward movement is always the same, but if the return movement is increased it will engage the ratchet one or two teeth in advance of normal position. Hence, when the screw strikes the periphery of 30 the control pawl, it will simply have a sufficient feeding movement to rotate sprocket 107 the space of one tooth, but when the gap occurs on the cam, the return movement of the extension or arm 128 is greater than before, and the pawl 35 will engage one or two teeth more than the normal single tooth, depending upon the depth of the gap, for if said gap is shallow, only one additional tooth is engaged by the pawl 106, while if much deeper, two or more extra teeth are thus 40 engaged in addition to said one tooth. The feeding movement of the pawl on rocking member will thus equal one, two or more teeth upon the sprocket, and the control cam will thus cause the feeding of the fabric through the feed rolls 45 to be speeded up past straight or nearly straight portions of rows of stitches in various designs. Naturally, the control cam is both cut to a predetermined depth and length of gap to correspond with the design involved, and also properly timed to present the gap to the screw or projection upon the extension 128, and the latter may itself be formed to engage the cam. The gap in the latter even has different depth 50 cut throughout its extent to correspond with different portions and curves in designs used, as occasion may require.

Upon extension 84 of one of the runners 4 (Fig. 5) a bracket 120 is fixed and a manually operated lever 121 is pivoted to said bracket at 122 and at its lower end 123 is connected by means of a link 124 to a downwardly extending lever 125, which is pivoted at its lower end to a pivotal mounting 126 fixed to the frame of the machine. A spring 127 is connected between the pivoted portion of manual lever 121 and the upper end of lever 125 so as to tend to return and retain said lever in idle position. Near the lower end of lever 125 an operating device 128 is secured, associated with clutch pulley 16 so that 65 if the manual lever 121 is drawn toward the right in the direction indicated by the arrow, the clutch pulley 16 and associated clutch 17 will become engaged upon the motor shaft and the machine will be directly operated by the mo- 70 75

tor if the latter is supplied with electric current.

In order to furnish the necessary current to operate the motor, a switch which may be, for example, a mercury switch 132 (Figs. 13 and 14) is rockably mounted in a switch casing 133 and has a starting arm 134 controlling the same, which arm is slotted at 137 and engages a stud or bolt 135 associated with the switch, so that when the arm is moved toward the left as indicated by the arrow, a cutout portion 137 will register with a catch 138 and allow the arm to drop a small distance and rock the switch 132 from its open idle position illustrated into closed position. The mentioned arm is connected at its outer end to lever 125 which is operated by manual lever 121 also capable of engaging the clutch 17 as already described, so that the clutch is engaged simultaneously with the turning on of the current for the motor.

The mentioned catch 138 is pivoted at 139 in a magnet casing 140 and has a yoke disposed in proximity to an electromagnet 142 in said casing 140. When the starting arm has been shifted toward the left and has dropped into engagement with catch 138, the latter will retain the arm in the attained position with the switch 132 in closed circuit position, but if a current is even momentarily supplied from some source to the electromagnet 142, the latter will attract yoke 141 of the catch and will thus swing the same downwardly in clockwise direction, releasing starting arm 134. This arm will then immediately shift toward the right, due to the action of the return spring 127, and meanwhile the slotted end of the arm as well as the switch will be returned to the inactive position shown in Fig. 14, stopping the motor.

The arm 125 will cause the yoke 141 and catch 138 to assume the positions shown when the motor is stopped, as the current in coil 142 is cut off and allows a spring 140 upon the coil to raise the yoke and swing the catch upwardly about its pivot 139.

A means for providing current to the electromagnet when required is provided, for example, in the form of a transformer 143 (Figs. 13 and 14) and if we refer to the electrical circuit diagram it will be readily seen that the current supplied from the mains at 144, 145, the current from the latter passing through the mercury switch 132 and from thence to the motor 18 through cable 146 and a fuse 147, while the motor is also connected to the return main 144, thus establishing the motor circuit controlled by the switch. From the same fuse 147 the cable 148 passes down to the winding 149 of transformer 143 while the return main 144 also completes the circuit of the latter, so that even the current supplied to the transformer is controlled by the mercury switch simultaneously with the motor.

The other winding 150 of the transformer is connected by cable 151 directly to the electromagnet 142, while the other terminal of said winding is connected to two branch cables 152, 153 to a manually operated stop button 154 and to a simple switch 155, respectively. From the stop button, a cable 156 connects on the one hand to a second fuse 157 through cable 158 which in turn connects with electromagnet 142 through a cable 159, completing the circuit of said magnet through push button 154. If said button is pushed, the current from transformer winding 150 will pass through the coils of the electromagnet, and if the machine is running and

switch 132 is closed position, due to locked position of starting arm 134, the latter will be released the mercury switch rocked back into idle position, opening the motor circuit so that the motor stops. Upon return of the starting arm, and with it, also the manual lever 125 to inactive position, the clutch 17 is also disengaged with its pulley from active mechanical connection with the motor. The stop button 154 is preferably mounted on a stop motion bar 160 fixed on the machine a distance above the presser foot (Fig. 1), and upon the same bar are secured one or a group of insulated contact bars 161 held out of contact upon said bars by means of insulating blocks, cleats or rings 162, 162.

Each contact bar 161 is connected to an individual switch such as indicated at 155, while from each such switch runs a cable 163 to the contact bar 161 associated therewith. Upon the stop motion bar 160 is secured a swivel or pivot rod 164 upon which an equal number of thread contact members 165 to the maximum number of needles upon the needle bar 34 are pivotally mounted. Each contact member 165 is provided with a thread guide 54, already mentioned and is normally held with its lower contacting portion 166 in active contact with contact bar 161 by means of a spring 167. For each such thread contact member 165 or restricted group thereof, there is a switch 155, so that for any idle group of needles on the machine, the corresponding switch 155 is left open in order to avoid affecting the operation of the remaining needles and other devices.

However, it has already been pointed out that the thread is only tightened during the upward stroke of the needle bar at the end of each stitch to tighten the latter, but it is quite conceivable that during such momentary tightening operation, a thread may break, due to excessive strain thereon or weakness of the thread. When the thread is thus tightened it draws the thread contact member 165 involved out of contact with contact bar 161, so that the circuit of the electromagnet is open, but if any thread breaks at that moment, the corresponding contact member 165 will instantly be drawn into active contact with its contact portion 166 against contact bar 161 by the associated spring 167, thus initially closing the circuit of the electromagnet so as to open the motor circuit and stop the motor. In order to make the stopping of the motor effective, but only during such intervals as when the thread is strained and tightened as described, a timing contact device generally indicated at 168 is interposed in the circuit just mentioned. This contact device consists of an insulated casing 169 within which a rotary contact member 170 is fixed on drive shaft 10 so as to be rotated thereby, while fixed in said casing is a stationary contact 171, and upon rotation of the shaft, the rotary contact member will make momentary electrical contact with contact 171, thus closing the electromagnet circuit, the thread contact member and the rotary contact member being both grounded to the machine.

The mentioned timing contact device is so adjusted and timed that it will close any and all circuits associated therewith only during the tightening operation of the threads upon the machine, inasmuch as this corresponds with the time when the thread contact members are also drawn out of electrical contact with the contact bar by the tightened threads. The useful interval of contact made by said rotary contact

is only a fraction of a revolution, for example, one eighth thereof, more or less.

The switch box or casing 133 preferably has a cover 172, while the rotary contact device just described is also provided with a cover 173. The contact bar and its associated parts is also protected by a cover bar 174.

- From the foregoing, it is evident that once the fabric and the threads have been properly placed in the machine and the same started by shifting manual lever 121 to the right, the mercury switch will close the motor circuit so as to start the same and will simultaneously throw in the clutch 17 so as to cause rotation of the drive shaft, with consequent reciprocal shifting of the movable frame or carriage from the position of Fig. 1 to that diagrammatically indicated in Fig. 6 and simultaneous operation of the sewing instrumentalities and predetermined rotation of the feed rolls. If it is desired to stop the machine, pressing of a button 154 will cause the motor to be cut out both mechanically and electrically, or if a thread breaks, the same result will ensue.

It is quite evident at this stage that the machine is wholly automatic in operation, allowing one operator to prepare further material and work for the machine while the latter is running and also to attend several such machines, while the box-spring and/or mattress border produced thereby will be readily made as heavy as desired and stitched along the lines of such designs, with such effective tightening of the stitches, that such borders will be resilient, strong and excellent articles of manufacture, which if bent or creased, will instantly spring back into straight or flat condition when released. The design is in every instance of substantially equal width throughout its length, the stitches crossing the warp and woof of the fabric, but does not extend to the two edges of the border but leaves margins free from stitches along said two edges, the latter being adapted to be sewed or otherwise secured to upper and lower fabric layers upon a mattress or box-spring. The machine described is particularly suitable for making such borders, and said borders are solely produced by the same machine.

Manifestly, variations of the borders and said machine for automatically making the same may be resorted to, and features and parts may be used without others.

Having now fully described my invention, I claim:

1. In an automatic multi-needle sewing machine having a fixed supporting frame, a drive shaft in said frame, and sewing instrumentalities mounted in the frame and actuated from said drive shaft, means for feeding fabric past said sewing instrumentalities and simultaneously shifting said fabric transversely back and forth with respect to the feeding direction of the fabric to produce stitched designs on the latter, comprising a rigid fabric frame slidably supported upon said machine having fabric feed rolls disposed adjacent to said sewing instrumentalities upon one side of the machine and driven from said drive shaft, said slidable fabric frame hav-

ing a portion disposed upon the same side of said machine as said feed rolls and serving to support a fabric wind up reel for receiving stitched fabric from said feed rolls, said slidable frame also having a second portion which is disposed on the other side of said machine in order to support a fabric supply reel for supplying fabric to said sewing instrumentalities, there being means for driving said drive shaft and means driven by said drive shaft for shifting said slidable frame, a cam fast on said drive shaft, a rocking member pivoted upon the movable rigid frame and having a portion engaging with said cam so as to rock said member upon rotation of the shaft, a gear train connected to one of the feed rolls and including a ratchet connected with and driving said gear train, a control cam having a generally circular profile interrupted by a gap of predetermined depth, form and length, a second rocking member on the movable frame connected to said first rocking member so as to be rocked thereby and carrying a pawl engaging with the teeth upon said ratchet, an arm rigid with said second rocking member having a portion striking upon the periphery of said control cam and being limited in movement thereby and thus limiting the movement of said pawl in one direction, and a second pawl pivoted upon said movable frame and engaging with the teeth of said ratchet to prevent return rotation of the latter, said control cam being rotated by said gear train and said arm portion having a greater stroke when encountering the gap in said control cam.

2. Means for controlling the form of a design sewed upon a sewing machine having a drive shaft, sewing instrumentalities driven from said drive shaft as well as fabric feed and take up means and thread supply, a stationary frame carrying said drive shaft and the sewing instrumentalities, and a horizontally reciprocable frame slidable with respect to said fixed frame and carrying said fabric feed and take up means, said controlling means comprising a cam on the drive shaft, a rocking member pivoted upon said reciprocable frame and having a portion making contact with said cam so as to be rocked thereby upon rotation of said shaft, rotatable means connected to said fabric feed means, a second rocking member pivoted on said reciprocable frame and connected to the first rocking member so as to be rocked by the same, means upon said second rocking member engaging with said rotatable means, a control cam having a gap in its periphery of predetermined form, size and depth, and being rotatable from said fabric feed means, a rigid portion upon said second rocking member striking upon said periphery of said control cam and being limited thereby and thus limiting the throw of said second rocking member and the means upon the same engaging with the rotatable means so as to vary the amplitude of the engagement, and means preventing reverse rotation of said rotatable means but allowing step by step movement thereof in one direction caused by said engagement from the second rocking member.

GUSTAV A. BOETTCHER.
